PUMP GOVERNOR

Bayler J. Fejedelem, Los Angeles, Calif.

Application July 6, 1954, Serial No. 441,581

10 Claims. (Cl. 103—16)

This invention relates to governors for use on pumps, particularly centrifugal pumps as used on fire trucks, and relates to an improved device for pressure maintenance therein.

In the employment of centrifugal pumps operated by a driving means such as a motor or engine, a problem in many applications of such pumps is the maintenance of a pressure which is relatively constant regardless of the demand upon the pump. This problem is particularly acute in the case of fire trucks, wherein the usual arrangement is that the internal combustion engine used for the propulsion of the truck itself is also used for driving the pump at the scene of the fire. The pumps are generally of the centrifugal type and are generally multiple and arranged so that they can be connected in series or parallel. The usual arrangement is that several fire hoses are fed by the same pump, and a problem arises whenever a nozzle is opened or, more particularly, suddenly closed, for example by a fireman operating one of the nozzles attached to one of the hoses. When a nozzle is suddenly closed, in the absence of any pump governing mechanism the pressure in the system will rise, and this is often sufficient to cause a reaction at the other nozzle being operated of sufficient magnitude to throw a fireman from a ladder or the like. Similarly, when a nozzle is open, the pressure in a multiple hose system tends to be lowered, and pressure must be restored in order for the fire to be combated with maximum efficiency.

Other difficulties arise when shifting from parallel feed to series feed, wherein it is desired to regulate at a higher pressure for the series feed. Any satisfactory pump regulator must be capable of operation of a large range of pressures, accordingly, and this taxes some regulators beyond their mechanical limits.

Many devices have been described for the maintenance of a constant pressure under the conditions described. For the most part, they are quite complicated mechanically, and there has been a continuing need for an improvement in the performance of available pump regulators.

An object of the invention is to provide an improved pump regulator for pressure regulation of a centrifugal pump maintained by a driving means.

Another object of the invention is to provide a fire pump governor of simple design.

Another object of the invention is to provide a fire pump governor which can be integral with the throttle mechanism used for control of the engine during propulsion of the truck, and not interfere therewith, yet being instantly available for pump pressure regulation during the operation of the pump.

Another object of the invention is to provide a pump governor readily adaptable to a range of pressures encountered in both parallel and series operations of fire pumps.

Another object of the invention is to provide a fire pump governor which is free of "hunting" tendencies.

Other objects of the invention will appear as the description thereof proceeds.

In the drawings,

Fig. 1 shows an illustrative embodiment of my novel 5 governor, attached to the carburetor of a fire truck.

Fig. 2 shows an enlarged and more detailed view of the interior construction of my novel governor, and in addition shows an additional adjustment in the mounting thereof.

10 Fig. 3 shows a cross-section through the assembly of Fig. 2 through the planes indicated by the dashed line 3—3 in Fig. 2.

Fig. 4 shows a modification of the method of mounting my novel governor on a carburetor.

15 Coming now to a description of my novel governor, reference is had to the drawings. In Fig. 1, 10 indicates a carburetor, which it will be understood is attached to the engine of a fire truck. 11 is the throttle shaft of the carburetor; the butterfly valve itself is indicated by dotted 20 lines, in Figs. 1 and 2. It will be observed that as the throttle shaft is rotated in a counterclockwise direction, the butterfly valve is opened.

Now in Fig. 1, 12 indicates a rod attached to the foot 25 throttle used in driving the truck; and 13 represents the hand control wire which is conveniently fixed to the instrument board of the fire truck, and is used for control of the throttle of the engine during the pumping operation at the scene of a fire. A clevis fitting 14 receives both the foot rod 12 and the hand wire 13; and a retracting spring 15 biases the throttle in the closed position. 30 The clevis fitting 14 is attached to an operating rod 16, which in turn is attached to the piston rod 17 of the governor assembly by means of a simple fitting 18.

The piston rod 17 is fitted into a cylinder assembly 19, 35 which is shown in cutaway detail in Figs. 1 and 2. The cylinder 19 is carried by a supporting fitting 20, which carries a horizontal rod 21 which passes through a slotted lever 22, which in turn is attached to the throttle shaft 11.

In the embodiment shown in Figs. 1, 2 and 3, the weight of the piston and cylinder assembly is borne by a link 23, which in the embodiment shown in Fig. 1 is attached to the carburetor body by a fixed bracket 24, and which in the embodiment shown in Figs. 2 and 3 is attached to the carburetor body through a substantially horizontal linkage 25.

40 It will be seen that retracting of the operating rod 16, which may be brought about through the action of either the foot rod 12 or the hand wire 13, will serve to open the throttle of the butterfly valve of the carburetor, and thus, if the engine is running, increase its speed.

Now attached to one end of the cylinder assembly is a 45 flexible hose 26. This is connected to the downstream side of the pump, so that it receives water under the fluid pressure developed by the pumps. The connection is preferably made through a fitting having greater resistance to flow in one direction than another, which is indicated in Fig. 1 by the check valve and bypass assembly 27. The tubing 28 leads to the pump mechanism 38.

Suppose that the pumps are started. The engine is then 50 accelerated by operation of the hand control wire 13, which moves rod 16 to the right, thereby opening the throttle. The wide-open-throttle position is shown in Fig. 2. Now suppose that at this particular setting of the engine, the pump pressure is too great, which might be caused for example by shutting off some of the fire hoses at the nozzles thereof. Water will be forced through tubing 28 and flexible hose 26 into the piston holder and cylinder assembly 19. This will exert a force against the compression spring 29 which is contained in the cylinder. 55 The cylinder will then move outwardly or to the left, with respect to the piston, and thus operate to close the throttle. Thus, a governing action is obtained. Should 60

the pressure drop, for example as the result of opening one or more fire nozzles, then the fluid pressure inside of the cylinder assembly 19 will be reduced, which will allow spring 29 to expand, and will thus move the cylinder to the right with respect to the piston, thus opening the throttle. The engine speed can be set at any desired value, by operating the hand control, and changes in pump pressure occurring thereafter will be offset and the desired pressure regained by the automatic operation of the governor in the manner just described.

A preferred embodiment of the piston and cylinder construction may be clearly seen in Fig. 2, wherein 30 designates a leather cup of the usual type. A slotted boss 31 is provided for the end of the piston to abut, so that even when the spring is fully expanded, a free passage for flow of water into the cylinder assembly is provided.

In the embodiment shown in Figs. 2 and 3, the link 23 which carries the weight of the governing assembly is attached to a horizontal linkage 25, which may be raised or lowered within limits by a bent lever 32, the position of which is adjustable by set screws 33 and 34. Where regulation at greatly differing pump pressures is desired, the operating range of the regulating action can be shifted by raising or lowering linkage 25 by suitable adjustment of lever 32 and set screws 33 and 34. For many installations, however, the simpler lever arrangement shown in Fig. 1 suffices.

The method of supporting the governor assembly wherein a separate link 23 is used as in the embodiments of Figs. 1 and 2, is preferable for use where the governor is installed on an existing engine. This is for the reason that in the average carburetor, the throttle-shaft bearings are not constructed for heavy duty, often being merely drilled in the die-cast body of the carburetor itself. However, where the bearings of the carburetor throttle shaft are adequate to carry the weight involved, the simplified assembly shown in Fig. 4 suffices, and serves to eliminate a number of mechanical parts. It will be seen that in the embodiment of Fig. 4 the governor assembly 19 is supported directly by the lever 22 attached to the throttle shaft, and the entire weight of the governor is placed upon the throttle shaft bearings.

I have found that in many instances, if free access of water from the pumps is permitted to the governor cylinder, the pressure control may be subject to repeated fluctuations, often termed "hunting." I have found that an effective way of controlling this tendency and of obtaining perfectly smooth response is to include an assembly, shown as 27 in Fig. 1, in the water supply line to the governor, which permits relatively free passage of water to the cylinder 19, but provides relative restraint to flow of water in the opposite direction, that is, out of cylinder 19, and back to the pump. This is readily accomplished by providing a check valve 35, which may be of common and simple construction, with the check action so arranged that the valve is open in the direction away from the pumps, and toward the governor. The check valve is bypassed by a needle valve 36, which is set with the needle slightly open, thus offering a restriction to return flow, since for flow in this direction the check valve will be closed. Thus, if pump pressure increases suddenly, as caused for example by the sudden shutting off of hose nozzles, then the throttle action is virtually instantaneous because water from the pumps flows without hindrance into cylinder assembly 19. However, if the pump pressure drops suddenly, as caused for example by the opening of hose nozzles, then the response of the engine is much slower, because in order for the engine to be accelerated, water must leave the cylinder 19 which it can do only by passing through the needle valve 36.

It will be seen that the invention accomplishes its objects. It will also be observed that the invention is a broad one, and it is desired to claim the invention broadly within the scope of this specification and appended claims,

particularly since many modifications of detail can be made, all within the scope thereof.

What I claim is:

- 5 1. In a fire truck including an engine, a carburetor attached thereto, rotatable throttling means attached to said carburetor, and including a throttle shaft, and at least one centrifugal pump operable by said engine: the combination of a lever arm attached to said throttle shaft; a cylinder pivoted to said lever arm; a piston within said cylinder; a spring within said cylinder and urging said piston to empty said cylinder; connecting means attaching said piston to a positionable hand control; and a flexible hose means communicating between said cylinder and said pump.
- 10 15 2. In a fire truck including an engine, a carburetor attached thereto, rotatable throttling means attached to said carburetor, and including a throttle shaft, and at least one centrifugal pump operable by said engine: the combination of a lever arm attached to said throttle shaft; a cylinder pivoted to said lever arm; a piston within said cylinder; a spring within said cylinder and urging said piston to empty said cylinder; connecting means attaching said piston to a positionable hand control; a fluid passage means communicating between said cylinder and said pump and including a by-passed check valve.
- 20 25 3. In a governor for regulating pump pressure in a fire engine including an internal combustion motor, at least one pump, a butterfly valve regulating air input to said motor; and a positionable throttle control; the combination of a link pivotally fixed to said motor and rotatable in a substantially vertical plane; a forked lever operating said butterfly valve; a shaft attached to the movable end of said link and engaging said forked lever; cylinder suspension means attached to the moving end of said link; a cylinder suspended by said suspension means; a piston within said cylinder including fluid sealing means at the end thereof within said cylinder; a compression spring urging said piston into said cylinder; a rod means connecting said piston and said positionable control; a flexible hose means connected to said cylinder; and a tubing means connecting said hose means to said pump.
- 30 35 40 45 50 55 60 65 70 75 80 85 90 95 4. The combination of claim 3 wherein fluid throttling means are interposed between said pump and said cylinder of a character permitting free flow of fluid to said cylinder but restricted flow of fluid from said cylinder.
5. The combination of claim 3 wherein said cylinder suspension carrying link is pivoted to a substantially horizontal lever which in turn is pivotally attached to said motor at a point horizontally displaced from the pivotal connection of said link and said lever, and adjusting means for raising and lowering said lever.
6. Throttle control means for operatively connecting a positionable hand control and a hydraulic centrifugal pump driven by an engine having a carburetor provided with rotatable throttling means attached thereto, comprising: a lever arm for attachment to said rotatable throttling means; a cylinder pivoted to said lever arm; a piston within said cylinder; a spring within said cylinder and urging said piston to empty said cylinder; connecting means for attaching said piston to said positionable hand control; and a flexible hose means for communicating between said cylinder and said pump.
7. Throttle control means for operatively connecting a positionable hand control and a hydraulic centrifugal pump driven by an engine having a carburetor provided with rotatable throttling means attached thereto, comprising: a lever arm for attachment to said rotatable throttling means; a cylinder pivoted to said lever arm; a piston within said cylinder; a spring within said cylinder and urging said piston to empty said cylinder; connecting means for attaching said piston to said positionable hand control; a fluid passage means including a by-pass check valve for communication between said cylinder and said pump.
8. Throttle control means for operatively connecting a

positionable hand control and a fire-engine-pump-operating internal combustion motor air-input-regulating butterfly valve; in combination, a pivot for fixation with respect to said butterfly valve; a link attached to said pivot and rotatable thereabout; a forked lever for attachment to and operation of said butterfly valve; a shaft attached to the movable end of said link and engaging said forked lever; cylinder suspension means attached to moving end of said link; a cylinder suspended by said suspension means; a piston within said cylinder including fluid sealing means at the end thereof within said cylinder; a compression spring urging said piston into said cylinder; a rod means for operatively connecting said piston and said positionable hand control; a flexible hose means connected to said cylinder; and a tubing means for connecting said hose means to said pump.

9. The combination of claim 8 wherein there is operatively connected with said tubing means fluid throttling means of a character permitting free flow of fluid to said cylinder but restricted flow of fluid from said cylinder.

5

10. The combination of claim 8 wherein said cylinder suspension means is pivoted to a substantially horizontal lever which is in turn pivotally attachable to said motor at a point horizontally displaced from the pivotal position of said link and said lever, and adjusting means for raising and lowering said lever.
